UNITED STATES PATENT OFFICE

167,793

PLASTIC FLOWERPOT COVER OR THE LIKE

Samuel W. Brunner, Flushing, N. Y.

Application January 15, 1952, Serial No. 18,079

Term of patent 3½ years

(Cl. D59—2)

To all whom it may concern:

Be it known that I, Samuel W. Brunner, a citizen of the United States, residing in Flushing, in the county of Nassau and State of New York, have invented a new, original, and ornamental Design for a Plastic Flower Pot Cover or the like, of which the following is a specification, reference being had to the accompanying drawing, forming part thereof.

Fig. 1 is a perspective view of a plastic flower pot cover or the like in an open position showing my new design.

Fig. 2 is a front plan view of that shown in Fig. 1 in a flat position, while

Fig. 3 is a rear plan view thereof.

I claim:

The ornamental design for a plastic flowerpot cover or the like, substantially as shown.

SAMUEL W. BRUNNER.
